[57] CLAIM

The ornamental design for an exercise board, as shown and described.

DESCRIPTION

FIG. 1 is a top plan view of an exercise board showing my new design;

FIG. 2 is a right side elevational view thereof;

FIG. 3 is an end elevational view thereof, the end opposite being substantially a mirror image; and

FIG. 4 is a top perspective view thereof.

FIG. 2

FIG. 1

FIG. 4

FIG. 3
